UNITED STATES PATENT OFFICE.

EDGAR W. ADAMS, OF EAST ORANGE, NEW JERSEY, ASSIGNOR TO WESTERN ELECTRIC COMPANY, INCORPORATED, OF NEW YORK, N. Y., A CORPORATION OF NEW YORK.

CALLING DEVICE.

1,284,206.

Specification of Letters Patent.

Patented Nov. 12, 1918.

Application filed April 24, 1917. Serial No. 164,273.

To all whom it may concern:

Be it known that I, EDGAR W. ADAMS, a citizen of the United States, residing at East Orange, in the county of Essex and State of New Jersey, have invented certain new and useful Improvements in Calling Devices, of which the following is a full, clear, concise, and exact description.

This invention relates to calling devices of the type employed in directly controlled machine switching telephone systems, and has for its object the provision of an improved form of calling device through the use of which the capacity of an exchange system may be greatly increased.

In telephone exchange systems, the practice has been to include not more than ten thousand subscribers in one exchange district, the system being divided into several such districts, each having a separate name. The usual telephone designation, then, consists of a name and a four digit number.

The advent of the automatic telephone has caused the exchange name to be left out of the designation and one or more digits to be substituted, with the result that in large systems it will be necessary to use six or even seven digits in a telephone number. This, however, is physiologically impractical, since it is generally admitted that the layman is only capable of remembering and sending numbers of five digits or less.

Another object of the invention, then, is to provide a calling device by means of which the conventional telephone number may be transmitted, it being an advantage to designate a telephone by a name and a number rather than by a longer number alone.

A feature of the invention is the use, in addition to a dial switch of any well-known type, of a number of keys, which may be operated before the dial switch and which will modify the impulses sent by the former in such a way as to extend the call to any given exchange district.

In certain telephone systems, two relays are provided, both responsive to the opera-

tion of the calling device. One of these relays is made responsive to weak currents and the other is made responsive only to strong currents. Hence, if the calling device is made to open the line entirely, both relays will fall off, but if the calling device introduces a resistance into the line, only the relay responsive to the strong currents will fall off. Such a scheme is shown in the patent granted to Roberts No. 1,148,800. The use of such a pair of relays and the manner in which their interactions may differently affect selective switches is shown in the patent granted to McQuarrie and Goodrum, No. 1,252,436, January 8, 1918.

According to the above-mentioned feature the character of any train of impulses is changed automatically without any discriminating action on the part of the subscriber, with the result that the same number of telephones may be called with the ten-position dial as with the double dial in the above-mentioned application.

In the preferred embodiment of the invention, as shown on the accompanying drawing, six keys are shown. By the actuation of never more than two of such keys, all possible combinations of affected and unaffected trains of impulses may be sent. With an appropriate designation of such keys exchange names may be used as will hereinafter appear.

It is intended that four trains of impulses be sent by the use of this calling device. The actuation of one key will change the character of the first train sent, the actuation of a second key will change the second train, and so forth. The actuation of the fifth key will change the first two trains of impulses sent and the actuation of the sixth key will change the character of the last two trains sent.

If now, we designate the keys 1 to 6 as North, South, East, West, Central and Main, and indicate those pressed by the number of keys, as above, zero indicating that no key has been pressed, and if we indicate the unaffected trains of impulses by the letter N, and the affected trains by the letter L,

we may call the same telephone number in sixteen different exchange districts after the manner of the following table:

5	Trains of impulses.	Keys pressed.	Designation of called telephone.
N N N N	0-0		1 2 3 4
L N N N	0-1	North	1 2 3 4
N L N N	0-2	South	1 2 3 4
N N L N	0-3	East	1 2 3 4
10 N N N L	0-4	West	1 2 3 4
L L N N	0-5	Central	1 2 3 4
N N L L	0-6	Main	1 2 3 4
L N L N	1-3	North East	1 2 3 4
N L L N	2-3	South East	1 2 3 4
15 N L N L	2-4	South West	1 2 3 4
L N N L	1-4	North West	1 2 3 4
L L L N	5-3	Central East	1 2 3 4
L E N L	5-4	Central West	1 2 3 4
L N E L	1-6	North Main	1 2 3 4
20 N L L L	2-6	South Main	1 2 3 4
L L L L	5-6	Central Main	1 2 3 4

According to the essential feature of this invention, then, the capacity of a ten thousand line exchange may be increased sixteen times.

It should be understood, however, that the invention is not to be limited to a ten thousand line exchange nor to the code of exchange names given above, as the principle is applicable to systems where either a larger or smaller number of digits are used in the designation of the telephones.

Other new and useful features will appear in the following detailed description and the appended claims.

Figure 1 is a side view of a telephone desk stand to which the calling device, embodying the features of this invention, is applied. Part of the desk stand is shown broken away so that a view of the interior may be had. Fig. 2 is a plan view of the same. Fig. 3 is a diagrammatic representation of the circuit connections of a calling device.

Six keys, numbered 1 to 6, inclusive, are provided, which, when pressed, set up circuit conditions to extend the calling line into any given exchange district. A dial switch 7 is also provided and may be of the type disclosed in the patent granted to Forberg, November 30, 1915, No. 1,161,854.

The subscriber, in manipulating the dial switch, places his finger in one of the finger holes and rotates the dial 8 in a clockwise direction until his finger strikes the stop 9. The stop 9, instead of being stationary as in the above mentioned patent, is attached to a shaft 10, to the lower end of which is secured an arm 11 carrying a pawl 12. Upon the movement of the arm 11, the pawl 12 engages the ratchet wheel 13, and rotates the arm 14 successively into engagement with the contacts 15, 16, 17 and 18, that is, upon the first rotation of the dial, the arm 14 will

be brought into engagement with the contact 15. The dial, in returning to its normal position, opens its contacts 19 in the well-known manner to send the train of impulses over the telephone line to which this apparatus is connected. Upon the second rotation of the dial the arm 14 will be moved into association with the contacts 16, etc.

A pawl 20 is provided to hold the ratchet wheel 13 in the positions to which it is successively moved.

The six keys, numbered 1 to 6, inclusive, are so arranged that, upon their depression, they are held in their actuated positions through the agency of individual latches 21, 22, 23, 24, 25 and 26.

27 designates the switchhook of the telephone. Secured to the switchhook is a rod 28, which is attached at its lower end to a bell-crank lever 29, and through such lever operates the rod 30. Rod 30, in turn, is loosely connected to a rod 31 which, upon the movement toward the left, draws each one of the latches 21 to 26 out of engagement with the buttons 1 to 6 in such a manner as to allow them to return to their normal positions under the influence of suitable springs (not shown). At the same time the rod 32, secured to rod 31, causes the movement of the locking pawl 20, whereby the arm 14 may be released and returned to its normal position, through the agency of the spring 37.

It should be noted that, in the operation of this calling device, the receiver of the telephone is first removed from the hook. This moves the rods 30, 31 and 32 to the right in such a manner that the latches 21 to 26 are made operative and the keys 1 to 6 may be depressed in any combination and be held in their actuated positions. The arm 14 may be rotated and will remain in its set positions since the movement of rod 32 has allowed the cam 20 to become operative. At the end of a conversation, when the receiver is replaced on the hook, the movement of the rods 30, 31 and 32 in the opposite direction will withdraw the latches 21 to 26 and the cam 20 to release the keys 1 to 6 and the arm 14 to their normal positions.

Suppose the keys 1 and 3 are depressed before the dial switch 7 is rotated. The current furnished to the telephone line from the central office travels over the line 33, the primary of the induction coil 34, the hook switch 35, the transmitter T, the contacts 19, and thence back to the central office over the conductor 36. The first manipulation of the dial 8 causes the movement of the arm 14 into association with terminal 15. Upon the return movement of the dial 8, the contact points 19 are actuated and the line circuit, above traced, is intermittently opened.

It will be noted however that the contact

19 is bridged by the resistance R through key 1, contact 15 and arm 14, hence the impulses transmitted at this time are affected, and the action of the selector switch, which receives the impulses, will be, in turn, affected.

Upon the second manipulation of the dial 8, however, the arm 14 is moved into association with the terminal 16, and, upon the return of the dial 8, and the consequent series of openings of the line circuit at the contact 19, an unaffected series of impulses will be transmitted which will differently affect the sector switch.

15 Upon the third manipulation of the dial 8, the arm 14 will be brought into association with the contact 17 and since the key 3 has been actuated, the series of impulses sent at this time will be affected.

20 Upon the last manipulation of the dial 8, the arm 14 will be moved into association with the terminal 18, and the train of impulses sent at this time will be unaffected in the manner previously described.

25 At the end of the conversation, the placing of the receiver on the hook will cause the return to normal of the keys 1 and 3, and the arm 14, as previously described.

What is claimed is:

30 1. In a calling device, an impulse transmitter for sending trains of like impulses, and a set of keys for modifying the character of all impulses in each of said trains of impulses.

35 2. In a calling device, an impulse transmitter for sending trains of like impulses, and a set of keys for modifying the electrical character of all impulses in each train of said impulses.

40 3. In a calling device, a dial switch for sending trains of impulses, a set of keys

for modifying the character of said trains of impulses, and means for operatively associating said keys with said dial switch.

4. In a calling device, a dial switch for 45 sending trains of impulses, a set of keys for modifying the character of said trains of impulses, and means controlled by the successive operation of said dial switch for operatively associating said keys with said 50 dial switch.

5. In a calling device, an impulse transmitter, a set of keys for modifying the character of impulses sent by said transmitter, and means responsive to the successive 55 operation of said impulse transmitter for operatively associating said keys with said impulse transmitter.

6. In a calling device, an impulse transmitter, means for modifying the character 60 of impulses sent by said transmitter, and means responsive to the successive actuation of said impulse transmitter for associating said impulse modifying means with said impulse transmitter.

65 7. In a calling device, an impulse transmitter for sending trains of impulses, a key for modifying the character of the first train of impulses sent, a key for modifying the character of the second train of impulses 70 sent, a key for modifying the character of the third train of impulses sent, a key for modifying the character of the fourth train of impulses sent, a key for modifying the character of the first and second trains of 75 impulses sent, and a key for modifying the character of the third and fourth trains of impulses sent.

In witness whereof, I hereunto subscribe my name this 20th day of April A. D., 1917. 80

EDGAR W. ADAMS.
